CLAIM

The ornamental design for a current-to-voltage transformer, as shown and described.

DESCRIPTION

FIG. 1 is a perspective view of a current-to-voltage transformer showing my new design;

FIG. 2 is a top plan thereof;

FIG. 3 is a side elevational view, the opposite side being the same as the side shown;

FIG. 4 is an end elevational view thereof;

FIG. 5 is an opposite end elevational view thereof; and

FIG. 6 is a bottom plan view thereof.
